UNITED STATES PATENT OFFICE.

ANTHONI KASLAITIS, OF NEW HAVEN, CONNECTICUT.

FUEL-IGNITER.

1,274,276.

Specification of Letters Patent. Patented July 30, 1918.

Application filed March 21, 1918. Serial No. 223,737.

To all whom it may concern:

Be it known that I, ANTHONI KASLAITIS, a citizen of Russia, residing at New Haven, county of New Haven, State of Connecticut, 5 have invented certain new and useful Improvements in Fuel-Igniters, of which the following is a specification.

This invention relates to improvements in fuel igniters and particularly to types 10 adapted to be applied to ordinary domestic stoves and ranges.

The principal object of the invention is to provide means whereby a gas flame may 15 be introduced below the grate so as to cause the fuel thereon to become ignited in a rapid and convenient manner.

Another object is to provide means whereby the igniter when not in actual use may be removed and a door provided to 20 cover the aperture through which the igniter is entered.

A still further object is to provide means whereby the igniter is supported closely adjacent to the grate when in an operative position.

These and other like objects are attained by the novel construction and combination of parts hereinafter described and shown 25 in the accompanying drawing, forming a material part of this disclosure, and in which:—

Figure 1 is a side elevational view showing a conventional type of range parts being broken away in order to show the application of the invention.

Fig. 2 is an enlarged fragmentary side elevational and sectional view of the same, the burners being shown in operative position.

Fig. 3 is a similar view showing the 40 burners removed from below the grate, and

Fig. 4 is a plan view as shown in Fig. 2.

In the drawings the numeral 10, indicates a stove or range, in the fire-box of which are transverse grate bars 11, below 45 and between the fire-bricks 12, covering the compartment 14, for ashes and the like, the grate bars being supported upon angle elements 16, the construction of the stove or range throughout being of the ordinary 50 type.

The invention comprises a fixed bracket 18, from which extend arms 19, the bracket being secured at the front of the range by any desired fastening means whatever.

55 Pivoted in the arms 19 of the bracket is a tube 20, one of its extending ends 21 being

reduced and suited to have engaged therewith a flexible gas hose leading to any convenient source of supply. Engaged in a projection 23, formed centrally of the tube 60 22, is a nipple 24, connecting with an elbow 25, from the other opening of which extends a pipe 27, the pipe sliding freely in a casing 28, from which it is prevented from being withdrawn by a collar 29.

At the outer end of the casing 28, is engaged the center element 31, of a T fitting 32 carrying in its end openings, nipples 33, by means of which are connected the outer 65 elbows 34, carrying the burners 35.

Formed with the casing 28, is a projecting lug 37, in which is pivoted a lever arm 38, having at its end a transverse pin 39, adapted to engage in a recess 40, formed in the bottom of the range and so located that 70 when the lever is in a substantially vertical position, as shown in Fig. 1, as to support the casing 28 and parts engaged therewith, holding the burners 35, in a substantially vertical position and, due to the telescopic 75 movement possible between the inlet pipe 27 and the casing 28, the burners may be moved to different points below the grate bars 11.

A sliding cover plate 42, is provided with 80 an actuating knob 43 at one end, and a pair of lugs 44 at the other, in which is engaged a rod 45, adapted to move within the slots 46, formed in guide plates 47, the slots having a hook shaped upper end 49 the arrangement being such that the cover plate may be 85 completely withdrawn from the opening 48, when it is desired to use the igniter, the arm 38 being extended so as to hold it in position, and when the igniter is withdrawn 90 the plate is raised and held in a raised position by engagement of the rod 45 in the ends 49 of the slots.

When it is desired to remove the igniter the arm 38 is folded upward and engaged 100 by a spring clip 50, the arm operating between fixed guides 51, so that when folded the burners move toward the front of the range, the igniter as a whole being rotated upon the axis 20, permitting it to enter the 105 opening 48, or be removed therefrom.

Proper connections having been made with the gas supply and the burners ignited, the cover plate 42 may be dropped as shown in Fig. 1, the igniter swung into position, as 110 shown in Figs. 1 and 2, and moved under the fuel to be ignited.

When the fuel has become ignited to a desired extent the telescopic casing element 28, carrying the burners, is pressed toward the elbow 25, and the lever support arm 38, 5 raised and engaged by the clip 50, at which time it may swing upon the support arms 19, completely outward from the range, the opening being covered by moving the sliding plate 42, to the position shown in Fig. 3. 10 From the foregoing it will be seen that a convenient igniter has been described, of sufficient capacity to ignite coal, or the like and that the same can be entered, removed, or otherwise maneuvered in an easy and 15 convenient manner.

I claim:

1. In a fuel igniter, the combination with a range having a fire-box, of a bracket attached to the front of said range, a gas pipe rotatably connected in said bracket, a tubular casing telescopically engaged with said gas pipe, a pair of burners supported by said casing, and a pivotal support arm by means of which said casing is held in a substantially horizontal position below said fire-box.
2. In a fuel igniter, the combination with a fire-box containing a grate, and a source of gas supply, of a bracket exterior of said fire-box, a tubular element rotatably supported in said bracket, said tubular element being connected with said source of gas supply, angular connections engaged with said tubular element, a telescopic casing slidably connected with said angular connections, a pair of burners attached to said telescopic casing, means for the inlet or outlet of said telescopic casing from said fire-box, a sup-

porting arm pivotally engaged with said telescopic casing, and means for holding said supporting arm in either of two adjusted positions.

3. In a fuel igniter, the combination with a source of gas supply, and a fire-box having a grate therein, of a bracket, a tubular element rotatably engaged in said bracket, a hollow connection extending from said tubular element, a telescopic casing surrounding the outer end of said connection, gas burners carried by said telescopic casing, means permitting said gas burners to be moved relative to the grate of said fire-box, and a pivotal support on said telescopic casing whereby it may be held extended horizontally.

4. In a fuel igniter, the combination with a range adapted to burn coal and having an opening at the lower front part thereof, a bracket secured over said opening, a tube rotatably engaged in said bracket, and connections between said tube and a source of gas supply, of an L shaped fitting connected with said tube, a collar at the extreme end of said L shaped fitting, a hollow casing engaging with said L shaped fitting, a pair of burners communicating with said casing, means for moving said burners horizontally within said opening, means for supporting said burners, said means being foldable, means for holding said support means when in a folded position, and a sliding door adapted to cover said opening when said casing is swung outwardly.

In testimony whereof I have affixed my signature.

ANTHONI KASLAITIS.
